FILLING TUBE

Howard Bentley and Robert Bentley,
Detroit, Mich.

Application June 8, 1945, Serial No. 598,400

3 Claims. (Cl. 220—86)

1

My invention relates to a new and useful improvement in a filling spout adapted for use on tanks, such as gasoline tanks to afford a means for depositing the liquid in the tank.

An object of the invention is the provision in a filling spout having a pair of telescoping tubes with the inner tube provided with a closure for closing the outer end and all so constructed and arranged that when the inner tube is thrust inwardly its full length, the closure of its outer end will lie flush with and in general appearance form a continuation of the surface of a fender or the like through which the filling spout is adapted to proceed.

Another object of the invention is the provision in a filling spout having an inner tube with a closed outer end provided with a gripping portion which is normally invisible.

Another object of the invention is the provision in a filling spout having a slidable inner tube with a closed outer end and provided on the outer surface of the closed end with a gripping portion corresponding to the surface of the body through which the inner spout is adapted to project.

Another object of the invention is the provision in a filling spout having a pair of telescoping tubes of a novel construction relating particularly to the sealing.

Another object of the invention is the provision in a filling spout having a tube of a construction so arranged that the sealing gasket may be sealed and quickly mounted therein.

Other objects will appear hereinafter.

It is recognized that various modifications and changes may be made in the detail of structure illustrated and it is intended that such variations may be encompassed within the scope of the claims which form a part hereof.

Forming a part of this specification are drawings in which

Fig. 1 is a central section or view of the invention with parts broken away and some shown in side elevation.

Fig. 2 is a view similar to Fig. 1 with the inner tube in the extracted position.

Fig. 3 is a fragmentary sectional view showing a slight modification.

Fig. 4 is a fragmentary sectional view showing a further modification.

In the drawing, I have illustrated the invention mounted on a tubular neck 9 which extends upwardly from a tank or container 10. An outer tube 11 formed preferably from sheet metal is connected by the flexible sleeve 12 to the neck 9.

In the drawing, I have illustrated the inven-

2

tion used adjacent an automobile fender 13 having an opening 14 formed therein and punched inwardly around the opening to provide the flange 15. The outer tube 11 is pressed outwardly at its upper end to provide the flange 16 which rests upon the upper face of the flange 15 and which may be suitably secured thereto by welding, soldering, riveting, or in any other suitable manner. The fender 13 thus serves as a supporting member for the outer tube 11 and when the outer tube 11 is mounted on a fender as indicated, the fender itself serves as a covering or protective shield for the tube.

Formed in the inner face of the tube 11, adjacent its upper end, is an annular groove 17 corresponding to a similar annular groove 18 formed on the inner surface of tube 11 adjacent the lower end thereof. Formed in the inner face of the tube 11 adjacent its upper end is a groove 19, and seated in this groove 19 is a ring 20 of sealing material such as rubber, felt, leather, or the like. Slidably mounted in the tube 11 is an inner tube 21 having a bead 22 formed on its inner end and provided with a plurality of circumferentially spaced apart axially directed slots 23.

Formed in the inner tube 21 adjacent the outer end thereof is a lateral opening 24 which is exposed when the inner tube is drawn outwardly as shown in Fig. 2 to receive the nozzle of a filling hose.

The outer end of the tube 21 is turned outwardly to provide the radial flange 25 which is bent angularly as at 26 and thence radially as at 27 to provide a structure for gripping the ring 28 of sealing material formed from rubber or other suitable material. When the tube 21 is thrust fully inwardly of the tube 11 the sealing ring 28 will engage the flange 16 and the bead 22 will have snapped into the groove 18. When the tube 21 is drawn outwardly as shown in Fig. 2 the bead 22 will have snapped into the groove 17 so that there is thus provided a yieldable or resilient means for resisting the movement of the tube 21 from open to closed position and from closed to open position. In the slidable movement of the tube 21 the ring 20 of sealing material will bear tightly against the periphery of the tube 21 so as to prevent leakage around the tube 21.

A plate 29 serves as a closure for the outer end of tube 21 and rests upon and is suitably secured to the outer face of the flange 25. As clearly shown in Fig. 1 when the tube 21 is moved to fully closed position the outer face of the closure 29

lies flush and forms a continuation of the outer face of the fender 13.

Formed in the closure 29 is a central opening 30 opening into a housing 31. Positioned in this housing 31 is a spring 32 pressing the disc 33 into position for closing the opening 30. When the tubes are in the position shown in Fig. 1 and it is desired to pull the inner tube outwardly, the disc 33 is thrust inwardly by a person's finger against the compression of the spring 31 allowing the finger to grip the closure 29 and draw the tube outwardly.

In Fig. 3 I have shown a slight modification.

A tube 21A corresponds to the tube 21, the flange 25A corresponds to the flange 25, and the ring 28A corresponds to the ring 28. The plate 29A corresponds to the closure 29. This plate 29A is provided with an opening. 30A corresponds to the opening 30. A disc 33A corresponds to the disc 33 and this disc 33A is pressed by the spring legs 34 into closing position, these spring legs being mounted on the crossbar 35.

In Fig. 4, I have illustrated the invention in which the tube 21B corresponds to the tube 21 of Fig. 1. A closure 29B is mounted on the tube 21B. Mounted on and extending across the closure 29B is a strip 40 corresponding in contour to a decorative strip of moulding shown in dotted lines. As shown the strip 40 has a raised portion to provide a finger grip. This illustration is presented to indicate the application of the invention to a structure which has a moulding strip mounted thereon.

What we claim as new is:

1. A filling spout of the class described, an outer tube; a supporting body for said tube having an opening formed therein, said tube extending outwardly from one side of said body and said opening; a flange on said body off-set inwardly therefrom around said opening and projecting radially of said outer tube to provide an inwardly off-set recess; an outwardly projecting flange on the end of said outer tube engaging with and secured to the flange on said body; an inner tube slidably mounted in said outer tube, one end thereof projecting beyond the end of said outer tube and extendable outwardly from the opposite side of said body; a securing structure on the outer end of said inner tube; a ring of sealing material carried by said securing member and engaging, upon inward sliding of said inner tube into said outer tube, with the flange of said outer tube for effecting a sealing engagement; a closure on the outer end of said inner tube, free from outward projections and extending outwardly beyond the periphery of said inner tube and lying with its outer surface flush with the surface of said surrounding body when forming a continuation of the contour thereof upon inward sliding of said inner tube its maximum distance and forming a closure for said recess.

2. In a filling spout of the class described, a supporting body having an opening formed therein; an outer tube secured at one end to said body in registration with said opening and projecting outwardly from one side of said body; an inner tube slidably mounted in said outer tube, one end thereof being adapted for projecting beyond the secured end of said outer tube; a closure for the projecting end of said inner tube, free from outward projections on its outer face, and adapted for lying with its outer face flush with the surface of said supporting body and forming a continuation of the contour thereof upon inward sliding of said inner tube its maximum distance, there being an opening in said closure; and spring pressed means for normally closing said opening.

3. In a filling spout of the class described, a supporting body having an opening formed therein, said body being inwardly off-set around said opening to provide a recess surrounding said opening inwardly off-set from the outer face thereof and a flange portion extending outwardly from said opening; an outer tube secured at one end to said body in registration with said opening and projecting outwardly from one side thereof; a flange on said end of said outer tube engaging the flange in said inwardly off-set portion; an inner tube slidably mounted in said outer tube, one end thereof being adapted for projecting beyond the secured end of said outer tube; a closure for the projecting end of said inner tube, free from outward projections on its outer face, and projecting beyond the periphery of said outer tube and of a diameter substantially the same as the diameter of said recess and adapted for lying with its outer face flush with the surface of said supporting body and forming a continuation of the contour thereof upon inward sliding of said inner tube its maximum distance and forming a closure for said recess.
